CLAIM

The ornamental design for a multifunction portable flashlight, substantially as shown and described.

DESCRIPTION

FIG. 1 is a top, front and right side perspective view of a multifunction portable flashlight, showing my new design; FIG. 2 is an alternative bottom, back and right side perspective view thereof;

FIG. 3 is a front view thereof;

FIG. 4 is a back view thereof;

FIG. 5 is a left view thereof;

FIG. 6 is a right view thereof;

FIG. 7 is a top view thereof; and,

FIG. 8 is a bottom view thereof.

1 Claim, 8 Drawing Sheets
